(57) **CLAIM**

The ornamental design for a signalling apparatus, as shown and described.

DESCRIPTION

FIG. 1 is a perspective view of the first embodiment of a signalling apparatus.

FIG. 2 is a top view of the first embodiment of the signalling apparatus.

FIG. 3 is a side view of the first embodiment of the signalling apparatus.

FIG. 4 is a bottom view of the first embodiment of the signalling apparatus.

FIG. 5 is a front view of the second embodiment of a signalling apparatus; and,

FIG. 6 is a perspective of the second embodiment of the signalling apparatus.

The broken lines depict portions of the signaling apparatus that form no part of the claimed design.
